US00D888629S

(12) **United States Design Patent** (10) **Patent No.:** **US D888,629 S**
Gander et al. (45) **Date of Patent:** **** Jun. 30, 2020**

(54) **VEHICLE HOOD**

(71) Applicant: **Oshkosh Corporation**, Oshkosh, WI (US)

(72) Inventors: **Jesse Gander**, Larsen, WI (US); **Christopher Yakes**, Oshkosh, WI (US)

(73) Assignee: **Oshkosh Corporation**, Oshkosh, WI (US)

(**) Term: **15 Years**

(21) Appl. No.: **29/706,533**

(22) Filed: **Sep. 20, 2019**

(57) **CLAIM**

We claim the ornamental design for a vehicle hood, as shown and described.

DESCRIPTION

FIG. 1 is a front perspective view of the claimed design;

FIG. 2 is a front view of the claimed design;

FIG. 3 is a rear view of the claimed design;

FIG. 4 is a left side view of the claimed design;

FIG. 5 is a right side view of the claimed design;

FIG. 6 is a top view of the claimed design;

FIG. 7 is a bottom view of the claimed design;

FIG. 8 is a detailed front perspective view of the claimed design; and,

FIG. 9 is a second front perspective view of the claimed design.

Evenly-spaced broken lines depict unclaimed environmental subject matter. Dash-dot broken lines depict unclaimed boundaries of the claimed design.

1 Claim, 9 Drawing Sheets

Related U.S. Application Data

application No. 14/724,279, filed on May 28, 2015, now Pat. No. 9,656,640, which is a continuation of application No. 13/841,686, filed on Mar. 15, 2013, now Pat. No. 9,045,014.
